(57) **CLAIM**

The ornamental design for a battery charger pedestal, as shown and described.

DESCRIPTION

FIG. 1 is a front-left perspective view of the battery charger pedestal of the present disclosure;

FIG. 2 is a front-right perspective view of the battery charger pedestal of the present disclosure;

FIG. 3 is a front elevational view of the battery charger pedestal of the present disclosure;

FIG. 4 is a rear elevational view of the battery charger pedestal of the present disclosure;

FIG. 5 is a left elevational view of the battery charger pedestal of the present disclosure;

FIG. 6 is a right elevational view of the battery charger pedestal of the present disclosure;

FIG. 7 is a top plan view of the battery charger pedestal of the present disclosure; and,

FIG. 8 is a bottom plan view of the battery charger pedestal of the present disclosure.

The broken lines shown in the drawings are for the purpose of illustrating portions of the battery charger pedestal that form no part of the claimed design.

1 Claim, 7 Drawing Sheets
